CARTRIDGE SYRINGE

Frank E. Brown, Burbank, Calif.

Application September 21, 1950, Serial No. 186,024

7 Claims. (Cl. 128—218)

1

This invention relates to, and has for its object the provision of, improved cartridge syringes (a cartridge syringe being an injection device comprising a cartridge containing the medicament, and a syringe adapted to receive and activate the cartridge to inject the medicament).

By this invention there is provided improved cartridge syringes which: do not require sterilization of the outside of the pierceable stopper of the cartridge before use; include simple means for aspiration (not involving a double-cell, aspirating test solution, and special stopper); (preferably) do not require a double-pointed hollow needle—whose stopper-piercing end must be resharpened and checked for straightness—but utilize an ordinary hypodermic needle (single point on hub), thus permitting use of any desired gage or length of needle as well as re-use of the needle after sterilization; and have other advantages which will be clear from the detailed description of various embodiments thereof given hereinafter.

The improved cartridge syringes of this invention essentially comprise two units, which when assembled and (where necessary) fitted with a hypodermic needle provide an operative injection device, one of these units (cap-cartridge, or cartridge-adapter) being discarded after use, and the other (syringe body) being either discarded (when unexpensively constructed for that purpose, e. g., of molded plastic) or re-used with other cap-cartridge units (in which case the syringe body may be of more permanent construction and materials, e. g., of metal).

The cap-cartridge unit of the cartridge-syringes of this invention essentially comprises: (A) a cap, in the form of a tubular body walled at one end, adapted to be rigidly connected with a syringe body, and having a passage through the walled end to the inside of the tubular body; (B) a medicament-containing cartridge having a slideable stopper at one end and a pierceable stopper at the other, the latter end being received in and telescopically connected with the tubular body of the cap; and (C) a removable cover closing said passage; the connection between the cartridge and cap being such that movement of the cartridge away from the walled end of the cap provides a reduced-pressure chamber therebetween.

The syringe body unit of the cartridge-syringes of this invention essentially comprises a hollow body adapted to receive a portion of the cartridge of the cap-cartridge unit therein and having means for rigidly connecting it with the cap of the cap-cartridge unit, and a plunger slidably mounted therein and adapted to operate the slideable stopper of the cartridge.

In the preferred embodiments of this invention, the cap-cartridge unit essentially com-

2

prises: a medicament-containing cartridge having a slideable stopper at one end and a pierceable stopper at the other, the latter end of the cartridge also being provided with an annular resilient flange; a cap having a needle-hub-engaging extension at one end and means at the other end for rigidly connecting it with a syringe body, a passage through the extension to the inside of the cap, and a stopper-piercing element mounted inside the cap, the cartridge being connected with the cap by a sliding fit of the resilient flange of the stopper inside the cap, the fit being such as to permit longitudinal movement of the cartridge in the cap without substantially admitting passage of air between the flange and the cap wall; and a removable cover on the extension. The invention will be described in detail in connection with the accompanying drawing, wherein: Fig. 1 is a plan view of a cap-cartridge unit embodying the invention; Fig. 2 is a plan view of a syringe body embodying the invention; Fig. 3 is an axial section of the unit shown in Fig. 1; Fig. 4 is an axial section of the syringe body shown in Fig. 2; Fig. 5 is a part axial section, part plan view of an injection device formed by the user's assembly of the cap-cartridge unit shown in Figs. 1 and 3 (the hub cover being removed) with the syringe body shown in Figs. 2 and 4 and with an ordinary hypodermic needle; Fig. 6 is a schematic view showing the position of the cartridge in the assembly after retraction of the cartridge to aspirate; Fig. 7 is a similar view showing the position of the cartridge at the start of the actual injection; Fig. 8 is a similar view showing the position of the cartridge and of the slideable stopper therein at the end of the actual injection; Fig. 9 is an axial section of another cap-cartridge unit embodying this invention, its assembly with a syringe body being indicated by broken lines and the cartridge being shown empty for simplicity of illustration; Fig. 10 is a fragmentary plan view of a cap-cartridge unit such as shown in Figs. 1 and 3 assembled with a modified syringe-body; Fig. 11 is a part axial section, part plan view of another cap-cartridge unit embodying the invention; Fig. 12 is a part axial section, part plan view of a syringe body adapted for assembly with the cap-cartridge unit shown in Fig. 11; Fig. 13 is a plan view of a cap for another cap-cartridge unit embodying the invention; Fig. 14 is a fragmentary axial section of a syringe body adapted for assembly with the cap (and cartridge) shown in Fig. 13; Fig. 15 is a part axial section, part plan view of another cap-cartridge unit embodying the invention; Fig. 16 is an axial section of another cap-cartridge unit embodying the invention, the cartridge being shown empty and without the slideable stopper for simplicity of illustration; Fig. 17 is an elevation of the open end of the cap.

shown in Fig. 16 (with cartridge removed); Fig. 18 is a part axial section, part plan view of another cap-cartridge unit embodying the invention; Fig. 19 is an end view of the unit shown in Fig. 18, with schematic indication of a step in the production of such unit; and Fig. 20 is a part axial section part plan view of another cap-cartridge unit embodying the invention. [The shapes and proportions of the various elements shown in these figures are illustrative only, and in some cases are deliberately exaggerated for purposes of clarity of illustration.]

Referring first to Figs. 1 and 3, the cap-cartridge unit shown comprises generally a cartridge 1, a cap 2 receiving one end of the cartridge, and a cover 3 on a needle-hub-engaging extension of the cartridge. The cartridge is essentially conventional, and is produced in the conventional manner; thus, it is formed of a tube of glass or equivalent material having stoppers 4 and 5 of rubber or equivalent material positioned in each end thereof to form a hermetically sealed container for an injectable liquid medicament 6. Stopper 4 is slidable in the bore of the tube and is provided with the conventional annular grooves (to enhance fit) and with an outwardly-opening threaded recess 7 adapted to receive a correspondingly threaded element on the syringe-body plunger. Stopper 5 has the conventional inwardly-extending recess (to minimize the thickness of rubber to be pierced by an axially-positioned hollow needle), and a flanged head 8, the diameter of the head being such as to slidably associate the stopper 5 (and hence cartridge) with the substantially cylindrical bore 9 of cap 2.

Cap 2 is of transparent material (e. g., plastic) and has the general shape of an open-ended cylinder. Its bore 9 terminates in a substantially flat face 10 from which extends an axially-positioned hollow needle 11 having a piercing point 12. The needle 11 passes through (and is fixed in) the end of wall of the cap and through the integral axial extension thereof 13; the external diameter and taper of the extension corresponding with the internal diameter and taper of the hub of a conventional hypodermic needle 14—15 (see Fig. 5). Extension 13 is provided with a frictionally-retained, removable cover 3 of rubber or equivalent material. The other end of the cap is provided with external (desirably fast) threading 17; and the cap is of enlarged diameter (and knurled, if desired) at an intermediate point 18, providing a handle for assembling the cap with the syringe body.

The frictional hold of slidable stopper 4 in the tube of the cartridge should be such that a pull on the stopper can retract the cartridge (i. e., move the cartridge in the cap away from the needle) without substantially moving the stopper in the cartridge (it being noted that stopper 5, by virtue of its flanged head, virtually cannot be pulled into the cartridge and hence assists in preventing stopper 4 from being pulled out); but the frictional hold should be insufficient to prevent stopper 4 from being pushed into the bore of the cartridge to expel the medicament through the pierced stopper 5. Stopper 5, on the other hand, is held against inward movement by its flanged head, and its frictional hold in the cartridge should be such as to prevent it from being pulled out on retracting the cartridge. The frictional hold of the flange 8 (of stopper 5 in the bore of the cap) should be sufficient to prevent unintended detachment of the cartridge from the cap and to prevent contamination of the aspiration chamber

formed by the cap and said flanged stopper; but the frictional hold of the flange should not be such as to prevent its sliding away from the needle 12 to aspirate, and sliding up to face 10 of the cap (the needle 11 meanwhile piercing the stopper).

The cartridge-cap and cover assembly is prepared under sterile conditions and/or sterilized after assembly, and the assembly packed (either singly, with or without a syringe body, or severally) in a suitable container e. g., of cardboard), desirably a container adapted to prevent accidental detachment of the cartridge from the cap during distribution. The portions of the assembly capable of introducing contaminants on injection (i. e., face of stopper 5, needle 11, and aspiration chamber) are substantially hermetically sealed off, and thus remain sterile until use; and those portions are not subject to contamination when associating this unit with the syringe body (which need not be sterile). Removal of cover 3 and attachment of a sterile needle require only the usual technique of avoiding contamination.

As shown in Figs. 2 and 4, the syringe body comprises an elongated hollow cylindrical body 20 of plastic or equivalent material, and a plunger 21 of plastic or equivalent material slidably mounted therein. Body 20 has a substantially cylindrical bore 22 between its ends, the diameter being such as to loosely receive cartridge 1; its cartridge-receiving end has internal threading 23 corresponding to the external threading on cap 2, enabling rapid joining of the cap with the syringe body into a rigid structure; and its other end has reduced bore 24 through which passes the plunger 21. The plunger has a rod portion 25 slidable in bore 24 and terminating at its outer end in an enlarged portion 26 shaped to provide a thumb rest; and to its inner end there is (permanently) attached, by tightly threading therein, an element (of metal, for example) having a disc-portion 27 or larger diameter than bore 24 (hence preventing the plunger from slipping out of the body 20) and a threaded axial extension 28 adapted to be engaged with the internal threading in stopper 4 of the cartridge. Also, body 20 is provided with an external annular flange 29 intermediate its length, providing a finger rest for operation of the injection device.

As shown in Fig. 5, the cap-cartridge unit shown in Figs. 1 and 3 is assembled with the syringe body shown in Figs. 2 and 4 and with a hypodermic needle, and the assembly is operated as an injection device as schematically shown in Figs. 6, 7 and 8. In assembling the units, the plunger is first retracted (beyond the position shown in Fig. 5), the cartridge inserted into the bore of the syringe body and the cap and syringe-body threads engaged; the threaded element on the plunger rod is then engaged with the threaded stopper in the cartridge; and the cover on the cap extension removed, and a sterile needle attached thereto (by slipping its hub on the extension and twisting).

In using this injection device, the needle is inserted into the patient, and, while holding the unitary cap and syringe body assembly with one hand, the plunger is retracted with the other (cf., Fig. 6). This action pulls the cartridge away from the needle and enlarges the aspiration chamber (cf., 30 in Fig. 5 and 31 in Fig. 6), the reduced pressure causing blood to issue into said chamber if the needle 15 is positioned in a vein; in that

case the needle is repositioned, unless, of course, intravenous administration is desired. The plunger is then pushed into the syringe body, forcing stopper 5 against the needle point 12 and causing the stopper to be pierced; and further pushing on the plunger brings the face of stopper 5 to a stop against inner face 10 of the cap (cf., Fig. 7). Then, further pushing on the plunger causes stopper 4 to slide through the bore of the cartridge, causing the medicament to pass out of the cartridge through needle 11 and the attached hypodermic needle into the patient (cf., Fig. 8). Alternatively, the cartridge is first pushed towards needle point 12 and stopper 5 pierced, and a drop of the medicament expressed through needle 15 (conventional technique, to assure there is no needle blockage); then the needle 15 is inserted into the patient, and the cartridge retracted to the position shown in Fig. 6, to aspirate; and if the needle is properly positioned, the cartridge is again pushed forward (needle point 12 re-entering stopper 5) and the medicament injected.

The alternative embodiment of the invention shown in Fig. 9 utilizes the identical cap as the unit illustrated in Fig. 2, but the cap is associated with a cartridge of the two-cell, by-pass type (which is the subject matter of my application Serial No. 109,430, filed August 10, 1949, now Patent No. 2,549,417, dated April 17, 1951). For the purposes of its utilization in conjunction with the present invention, said cartridge need be only generally described. It is formed of a tube 32 of glass or equivalent material having stoppers 33 and 34 of rubber or equivalent material positioned in each end thereof to form a hermetically-sealed container, and a partition 35 of rubber or equivalent material positioned between stoppers 33 and 34 to provide two noncommunicating chambers 36 and 37. Chamber 36 contains a medicament (of the type which is desirably not added to the diluent until just before use), and chamber 37 the diluent therefor. Stopper 33 (like stopper 5 in the embodiment shown in Fig. 3) has an inwardly-extending recess and flanged head; and stopper 34 (like stopper 4) is slidable in the bore of the tube and has a threaded recess to receive the threaded element on the syringe-body plunger. Partition 35 is slidable in the bore of the tube; and adjacent said partition, in the chamber 36, the tube has a longitudinally-extending deformation 38 longer than partition 35, the deformation being such that when the partition 35 moves to the position indicated by dotted lines, the diluent can by-pass the partition by means of said deformation.

The cap-cartridge unit shown in Fig. 9 is adapted to be used with a syringe body of the same general type as that shown in Figs. 2 and 4, such assembly being indicated by broken lines. Necessarily, the body portion and rod portion will have to be made longer than their counterparts in the syringe body shown in Figs. 2 and 4, to accommodate the longer cartridge; and the same elongated syringe body obviously may be used with either the simple (short) cartridge of Figs. 1 and 3, or the by-pass (elongated) cartridge shown in Fig. 9.

In the embodiment of the invention shown in Fig. 10, the cap-cartridge unit is the same as shown in Figs. 1 and 3, and the syringe body is the same as that shown in Figs. 2 and 4—except that the body 39 is provided with two (or more) substantially diametrically-positioned, longitudinally-extending slots (of which one, 40, is shown). 70

These slots are so positioned and/or of such length as to expose part of cartridge 1 when the cartridge is in the aspiration-beginning position (cf. Fig. 5). This embodiment of the invention enables aspiration by retracting the plunger as described hereinbefore; or optionally, by holding cap 2 with fingers of one hand, gripping the syringe body and cartridge (through the slots) with the fingers of the other hand, and rotating the syringe body (in the unthreading direction) while holding the cap stationary, the cartridge following the motion of the syringe body and hence being retracted in the aspiration chamber. Alternatively, the threaded recess in the slidable stopper of the cartridge and the threaded element on the plunger rod may be omitted, and aspiration accomplished solely by the (partial) unthreading operation described.

The embodiment of the cap-cartridge unit shown in Fig. 11 and the embodiment of the syringe body to be used therewith shown in Fig. 12 correspond generally to the respective units shown in Figs. 3 and 4, the difference being primarily in their adaptation for assembly and aspiration. Thus, the unit shown in Fig. 11 differs in that: the external threading 41 thereon is a short turn and relatively slow, and spaced from the annular extension 42; and (desirably) the internal threading in the sliding stopper of the cartridge is omitted. The unit shown in Fig. 12 differs in that: the body 43 has slots therein (one, 44, being shown) similar to those in the syringe body shown in Fig. 10; two sets of internal threading, 45 and 46 (corresponding to the external threading 41 on the cap) are provided in the bore of the body, providing in effect interrupted threading, the intermediate portion 47 being of such diameter as to slidably receive threading 41 on the cap; and (desirably), the threaded element on the plunger rod is omitted.

The units shown in Figs. 11 and 12 are assembled by threading (cap) threading 41 through (body) threading 45, and sliding the cap further into the body until threading 41 is adjacent threading 46. Aspiration is then accomplished by gripping the cap with the fingers of one hand, and the syringe body and cartridge (through the slots) with the fingers of the other hand, and pulling the syringe body and cartridge away from the (stationary) cap, threading 45 then acting as a stop to prevent the two units from being pulled apart. The syringe body and cartridge are then returned to initial position, and threading 46 engaged with threading 41 to provide a rigid assembly.

Alternatively, the two sets of threading may be provided on the outside of the cap (i. e., additional threading provided adjacent extension 42), and only one set of internal threading 45 provided in the bore of the syringe body, the assembly of the units and operation being effected in the same manner as described in connection with Figs. 11 and 12.

The cap shown in Fig. 13 and the syringe body shown in Fig. 14 correspond generally to the cap and syringe body shown respectively in Figs. 1-3 and 2-4, the difference being in their adaptation for assembly. Thus, in the cap shown in Fig. 13, the external threading is replaced by substantially diametrically positioned lugs 47 and 48; and the syringe body shown in Fig. 14 is provided with bayonet slots adapted to receive these lugs (only one slot, 49, being shown). The cap is assembled with the syringe body by first inserting the cartridge associated with the cap into the

syringe body, then pushing the lugs of the cap into the longitudinally-extending arms of the bayonet slots, and finally relatively-rotating the cap and syringe body to force the lugs into the circumferentially-extending arms of the bayonet slots. Preferably, the bayonet slots are of such shape and in such position that the cap is "locked" in position, i. e., offers substantial resistance to relative rotation of the parts for separation.

In the cap-cartridge unit shown in Fig. 15, the fixed hollow needle (for piercing the cartridge stopper) is replaced by a "floating" needle, obviating the relatively-expensive operation of fixing the needle in the cap. The end wall and extension of the cap are provided with a passage 50 adapted to slidably receive a single-pointed hollow needle 51 having a disc 52 fixed thereon intermediate its length (e. g., by staking). The non-pointed end of the needle is normally positioned so as to extend beyond the end of the extension on the cap, the extension cover 53 being suitably modified to accommodate this extra length. Such needle is "loosely" assembled with the cap by merely positioning it through the open end of the cap before the cartridge is inserted, the cartridge retaining the "floating" needle in the cap.

In operation, engagement of the hub of a conventional hypodermic needle with the extension causes the "floating" needle to move toward and pierce the cartridge stopper; the aspiration and injection operation being the same as that described in connection with the embodiment shown in Figs. 1-5.

In the embodiment shown in Figs. 16 and 17, both a fixed and "floating" needle in the cap are dispensed with. The external form of cap 54 conforms generally to that of the cap shown in Figs. 1 and 3—except for the more readily illustrated lugs replacing the threading, as in Fig. 13. The end wall 55 and hub-engaging extension 56 are provided with a passage 57; and adjacent the entrance of this passageway into the cap, there is provided (preferably integrally, by molding) a piercing point 58. The cartridge shown conforms generally to that of the cap-cartridge unit shown in Fig. 3—except that the flanged pierceable stopper 59 (of rubber or equivalent flexible material) is formed with a relatively thin, internally-domed central portion 60. Preferably (as shown more clearly in Fig. 17) the cutting point 58 is in the form of an off-center sliver adapted to cut a flap in the pierceable stopper 59, and thereby provide an opening overlapping the entrance of passage 57. For distribution of this embodiment, the cartridge may be pushed into the cap until the stopper is positioned against the end wall of the cap, thus providing a more stable unit (i. e., more securely engaged, providing a more extensive seal between the stopper flange and the cap, and obviating any possibility of the stopper being accidentally pierced during distribution).

The cap-cartridge unit shown in Figs. 16 and 17 is assembled with a syringe body such as shown in Figs. 2 and 4 (but having bayonet slots in place of threading), the protective cover 61 is removed, and a conventional hypodermic needle attached to extension 56. Then, after aspiration as described hereinbefore (by retraction of the cartridge in the cap), the cartridge is pushed back into the position shown in Fig. 16; pushing on the slidable stopper of the cartridge then urges the domed portion 60 of the pierceable stopper to flex outwardly, causing it to be pierced; and

further pushing on the slidable stopper causes the medicament to leave the cartridge and be injected (contact of the medicament with the walls of the chamber formed by the domed stopper and cap being immaterial, since that chamber has been pre-sterilized and maintained sterile).

In the embodiment shown in Figs. 18 and 19, means are provided for preventing accidental or undesired detachment of the cartridge from the cap (especially for preventing potentially dangerous re-use of the cap by re-assembling it with another cartridge). The cap shown conforms generally to that shown in Figs. 1 and 3 (with lugs in place of threading)—except that the open end of the cap is provided with two or more (four being shown) inwardly-extending deformations 62, 63, 64, 65, extending substantially to the outer surface of the cartridge. These deformations are formed, after insertion of the cartridge, by suitably supporting the cap-cartridge unit and bringing appropriately-shaped heated tools (illustrated by broken lines in Fig. 19) against the outer surface of the (thermoplastic) cap, and moving them towards the center until the desired deformations are formed. The cartridge in this embodiment conforms generally with that shown in Fig. 3—except that (preferably) the pierceable stopper end thereof is provided with an annular bead 66 of a diameter less than the internal diameter of the cap but sufficient to prevent its passing the deformed portion of the cap.

In the embodiment shown in Fig. 20, no stopper piercing element is carried by the cap, sacrificing certain of the advantages of this invention but resulting in further simplification. The cartridge is the same as that shown in Fig. 3; and the cap differs from that shown in Fig. 3 in that the needle is omitted, and the extension 67 is provided with external threading 68 (preferably tapered) and with a passageway 69 leading through the end wall of the cap and of sufficient diameter to slidably receive the piercing end of a double-pointed hollow needle. The extension is closed (during distribution of the unit) by a threaded cap 70. In using this embodiment, the cap-cartridge unit is assembled with a syringe body, cap 70 removed and replaced by a double pointed needle having a threaded-hub engaging threading 68, and the cartridge syringe then operated in the same manner as that shown in Fig. 5, the double-pointed needle being of course reusable. Alternatively, the extension 67 may be omitted, and the passageway through the end wall enlarged and internally threaded (preferably flared) to receive an externally threaded member which is fixed intermediate the ends of a double pointed needle.

Other embodiments of the invention (including combinations of various features of the different embodiments described hereinbefore) will readily occur to those skilled in the art. A number of these are generally described hereinafter, detailed description and illustration by drawing being deemed unnecessary in view of the large number and representative nature of the embodiments shown in the drawing and described in detail hereinbefore.

Again sacrificing some of the advantages of the invention but with attendant simplification, the cap may have fixed therein a double-ended needle, with a cover on the extension enclosing the outer needle and thus maintaining it and the aspiration chamber sterile.

The slidable connection of the cartridge with the cap may be effected in the following addi-

tional ways, *inter alia*: by means of a ring of resilient material (separate from the pierceable stopper) gripping the cartridge and having a sliding fit in the cap; by means of a ring of circular cross section gripping the cartridge and adapted to slide or roll in the cap as the cartridge is moved longitudinally in the cap; and by means of a substantially sliding fit between the cartridge itself and the cap, with an annular band of lubricant therebetween.

The needle extending into the cap for piercing the cartridge stopper (cf. Fig. 3) may be fixed in the cap in the conventional manner, e. g. by molding the plastic cap around it. In such case, the non-piercing end of the needle should preferably extend beyond the end of the hub-engaging extension, to prevent any plastic entering the needle during the molding operation.

The various features shown and/or described hereinbefore may be combined in various other ways to provide still other embodiments of the invention. Thus, the by-pass cartridge shown in Fig. 9 may be made a component of the modified cap-cartridge unit shown in Figs. 11, 15, 18 and 20; and the slots shown in Fig. 10 may be provided in the syringe body shown in Figs. 2, 4 and 5, the threaded extension on the rod and threaded recess in the slidable stopper being then omitted, and aspiration being accomplished by merely retracting the cartridge with the fingers through the slots.

The invention may be variously otherwise embodied within the scope of the appended claims.

I claim:

1. A cartridge syringe comprising a syringe body and a cap-cartridge unit assembled therewith: said syringe body essentially comprising a hollow body adapted to receive a portion of the cartridge of the cap-cartridge unit therein and having means for rigidly connecting it with the cap of the cap-cartridge unit, and a plunger slidably mounted therein and adapted to operate the slidable stopper of the cartridge: said cap-cartridge unit essentially comprising (A) a cap, in the form of a tubular body walled at one end, adapted to be rigidly connected with the syringe body, and having a passage through the walled end to the inside of the tubular body, (B) a medicament-containing cartridge having a slidable stopper at one end and a pierceable stopper at the other, the latter end being received in and telescopically connected with the tubular body of the cap, and (C) a removable cover closing said passage; the connection between the cartridge and cap being such that movement of the cartridge away from the walled end of the cap provides a reduced-pressure chamber therebetween.

2. A cap-cartridge unit for assembly with a syringe body to provide a cartridge syringe, essentially comprising: (A) a cap, in the form of a tubular body walled at one end, adapted to be rigidly connected with a syringe body, and having a passage through the walled end to the inside of the tubular body; (B) a medicament-containing cartridge having a slidable stopper at one end and a pierceable stopper at the other, the latter end being received in and telescopically connected with the tubular body of the cap; and (C) a removable cover closing said passage; the connection between the cartridge and cap being such that movement of the cartridge away from the walled end of the cap provides a reduced pressure chamber therebetween.

3. A cartridge syringe comprising a syringe

65

70

75

body and a cap-cartridge unit assembled therewith; said syringe body essentially comprising a hollow body adapted to receive a portion of the cartridge therein and having means at one end for rigidly connecting it with the cap of the cap-cartridge unit, and a plunger slidably mounted therein at the other end and adapted to operate the slidable stopper of the cartridge: said cap-cartridge unit essentially comprising a medicament-containing cartridge having a slidable stopper at one end and a pierceable stopper at the other, the latter being provided with an annular resilient flange, a cap having a needle-hub-engaging extension at one end and means at the other end for rigidly connecting it with the syringe body, a passage through the extension to the inside of the cap, and a stopper-piercing element mounted inside the cap, the cartridge being connected with the cap by a sliding fit of the resilient flange of the stopper inside the cap, the fit being such as to permit longitudinal movement of the cartridge in the cap without substantially admitting passage of air between the flange and the cap wall, and a removable cover on the extension.

4. A cap-cartridge unit for assembly with a syringe body to provide a cartridge syringe, essentially comprising a medicament-containing cartridge having a slidable stopper at one end and a pierceable stopper at the other, the latter being provided with an annular resilient flange, a cap having a needle-hub-engaging extension at one end and means at the other end for rigidly connecting it with the syringe body, a passage through the extension to the inside of the cap, and a stopper-piercing element mounted inside the cap, the cartridge being connected with the cap by a sliding fit of the resilient flange of the stopper inside the cap, the fit being such as to permit longitudinal movement of the cartridge in the cap without substantially admitting passage of air between the flange and the cap wall, and of a removable cover on the extension.

5. A cap-cartridge unit as defined by claim 4, in which the internal diameter of the mouth of the cap is less than the external diameter of the pierceable-stopper end of the cartridge, thus preventing detachment of the cartridge from the cap.

6. A cartridge syringe as defined by claim 3, in which the cap and syringe body are correspondingly threaded to effect a rigid connection therebetween, and in which one of these has its threading interrupted to permit free longitudinal movement of the cap and syringe body relative to each other for the extent of the interruption.

7. A cap-cartridge unit as defined by claim 4, in which the stopper-piercing element is a single-pointed hollow needle passing through the extension to the inside of the cap and terminating there in a piercing point.

FRANK E. BROWN.
